UNITED STATES PATENT OFFICE.

ALMYR L. NEWMAN, OF WARWICK, RHODE ISLAND.

CLASP FOR BRACELETS.

Application filed March 2, 1928. Serial No. 258,605.

This invention relates to flexible bands, chains or linkages used as articles of jewelry such as bracelets, and particularly to an improved clasping-device for connecting opposite sections of the bracelet whereby they may be readily and conveniently uncoupled in applying the bracelet to or removing it from the wrist.

A particular object of the invention is to provide a clasping-device for connecting two adjacent links in a flexible or expandable bracelet to effect a secure coupling between the parts without liability of their becoming accidentally unclasped.

Another object of the invention is to provide a clasping-device wherein the coupling- or clasping-means may be folded closely against the bracelet link or unit to provide a smooth unbroken surface without sharp edges or projections liable to catch in the garments of the wearer.

Another object of the invention is to provide a clasping-device which is neat and more finished in appearance, and sturdier and more durable in use than similar devices heretofore employed for like purposes.

Further objects of the improvement are set forth in the following specification which describes a preferred form of construction of the invention as illustrated by the accompanying drawings. In the drawings:

Fig. 1 is a perspective view illustrating a conventional type of flexible wrist-watch bracelet and showing my improved clasping-device as applied to use therewith;

Fig. 2 is an enlarged longitudinal sectional view of the bracelet with its link-elements shown in section on the line 2-2 of Fig. 3, and one of the links illustrated as embodying the present improved clasping-device;

Fig. 3 is a plan view of the link-elements shown in part section on the line 3-3 of Fig. 2;

Fig. 4 is a cross-sectional view of the link unit carrying the clasping-device, taken on line 4-4 of Fig. 2;

Fig. 5 is a composite view showing one of the box-link units of the bracelet in perspective and also illustrating the center link which carries the clasping-device with the clasp shown as open; and

Fig. 6 is a perspective view of the inner slide-link of the bracelet.

The present improved clasping-device is adapted for use with various types of flexible and expandable link bracelets such as

commonly used on wrist-watches, and I have preferred to herein illustrate a form of construction of the bracelet as disclosed in my copending application for Letters Patent 60 Serial No. 205,117, filed July 12, 1927.

As herein shown the bracelet proper comprises a series of outer tubular box-links 2 assembled with inner slideable connecting-links 3 which are normally maintained telescoped within the box-links under tension of suitable coil-springs 4. In Figs. 2 to 6 of the present drawings the link-elements are shown in inverted position or bottom side up as compared with the position they assume in the bracelet. The box-links 2 are formed with relatively flat top-portions 5 having sides 6 bent at right-angles thereto, and bottom-portions 7 folded inwardly therefrom with their edges meeting in closely abutting relation at 8. The bottom-sections 7 of the box-link 2 have tabs or extensions 9 at one end which are folded inwardly and cut away to form a cross-bar 10 to provide means for coupling or hooking the next adjacent slide-link thereto. The opposite end of the box-link 2 is provided with ears or tabs 11 bent inwardly to serve as abutments for the spring 4, the ears being spaced away from the sides 6 of the link to adapt the sides of the slide-link 3 to slide therebetween.

The inner slide-link 3 takes the form of a shallow tray having a relatively flat top-portion 15, sides 16 bent at right-angles thereto and an end-strip 17 extending between the sides. At its opposite end the top-portion 15 is extended beyond the sides and bent around to form a hook 21, see Figs. 2 and 3. The hook 19 on one of the slides, shown in Fig. 6, which is employed for connection with the link carrying the clasp-member is cut away to form a rectangular slot or opening 20, see also Fig. 5. The slides 3 are inserted in the tubular box-links 2 before the end-tabs or ears 11 are folded inwardly from its bottom-strips, the spring 4 being placed inside the slide-link with one end abutting its end-strip 17. The ears 11 are then bent downwardly to engage the opposite end of the spring to hold it under compression whereby its acts to normally maintain the slides telescoped within the box-link 2 while providing for drawing it out therefrom to expand the bracelet. The hooks 21 on the slides 3 which are connected permanently with the adjacent box-links 2 are narrowed or cut away at their ends to

adapt them to be inserted through the openings between the tabs 9 and bent around the cross-bars 10 in the manner as shown in Figs. 2 and 3 of the drawings. This construction provides for assembling the link-units with the slide 3 in one box-link 2 hingedly coupled to the end of the next adjacent box-link in the series.

In the present type of flexible and expandable bracelet it has heretofore been the usual practice to couple the link-units together permanently, for example in the manner as last explained, and with this arrangement it is necessary to stretch or extend the bracelet in slipping it over the hand when applying it to or removing it from the wrist. It has been found, however, that this repeated stretching or extending of the link-elements soon weakens the springs so that they lose their tension and fail to act to maintain the links in telescoped or contracted relation. The connections between the links of the bracelet therefore become loose with the joints open so that the bracelet does not sit snugly on the wrist.

Bracelets of the present type generally have a fastening-device or clasp 22 at either end, as shown in Fig. 1, for attachment to the bails of the wrist-watch and in some instances these clasps are resorted to for fastening the bracelet in place on the wrist and removing it therefrom. The bail clasps, however, are not intended for this purpose and are liable to get out of order and become insecure for attaching the bracelet to the wrist-watch. It has therefore been proposed to provide a clasping-device at the center of the band or bracelet for fastening its two opposite sections together to provide for its convenient application to and removal from the wrist. It is the object of the present invention to provide a clasping-device for this purpose and the improved construction and arrangement of the device will next be described in detail.

Usually the clasping device is applied to the central link in the bracelet so that it may be divided into two equal sections when it is unclasped to place it on or remove it from the wrist. In the present construction the central box-link 23, shown in detail in Fig. 5, is of substantially the same form and arrangement as the other box-links 2, having a flat top-portion 24, sides 25 bent downwardly therefrom and bottom-strips 26 folded over to meet at the center. At one end of the box-link 23 are tabs 27 bent down to form a cross-bar 36, shown in Fig. 2, similar in construction to the cross-bar 10 on the other box-links 2. The opposite end of the box-link 23 is constructed without the inwardly bent tabs or ears, but is provided with a cross-pin 28 reaching across its opening with its ends riveted through holes in the sides 25. The top-portion 24 is cut away

at this end of the link to provide a recess 29 for receiving the end of the clasp 30 to be next described.

The clasp 30 is of bifurcated shape, comprising a cross-strip 31 connecting the ends 70 of two arms 32 which straddle the sides of the box-link 23 and are fastened to the ends of a pivot-pin 33 reaching therethrough. The pivot-pin 33 projects through holes in the sides 25 of the link 23 and its ends are 75 riveted or swaged over to hold the latch 30 in place. At the center of the cross-strip 31 is a relatively narrow strip or tab 34 bent into involute shape to form a latch adapted 80 to slide across and spring into place in hooked relation with the cross-pin 28 at the end of the link 23. The forward edge of the cross-bar 31 is beveled off on its under side, as shown most clearly in Fig. 5, to provide 85 a lip 35 beneath which the fingernail may be inserted to facilitate lifting the latch to disengage it from the cross-pin 28. The latch or hook 34 is adapted to slide through the opening 20 in the end-hook 19 on the slide 3 after the latter has been hooked around the 90 cross-pin 28, as shown in Fig. 2 of the drawings.

The method of operation of the clasping-device in coupling and uncoupling the two parts of the bracelet is as next explained: 95 The two sections of the bracelet are laid around the wrist, their ends brought together and the hook 19 on the slide 3 hooked around the cross-pin 28 on the box-link 23; the clasp or latch-member 30 being in open position during this operation as indicated by the dotted lines in Fig. 2. The finger is then pressed against the cross-bar 31 of the clasp 30 to swing it into place to carry its latch 34 through the opening 20 in the hook 19 whereby to cause its end to snap over the pin 28 and to engage frictionally therewith. The resiliency of the latch 34 maintains it in this locking engagement with the pin 28 and the clasp is thereby securely fastened to prevent uncoupling of the parts of the bracelet; it being understood that the hook 19 is prevented from release from the pin 28 through the interengagement of the latch 34 with the opening 20 in the hook. That is to say, the hook 19 is held from being turned to such an extent as to release it from the pin 28 or from moving back or raising up to effect such release.

To unfasten the two ends of the bracelet-sections it is only necessary to insert the fingernail under the lip 35 on the clasp 30 to raise or swing the latter away from the top of the box-link 23, whereby the latch 34 is withdrawn from engagement with the pin 28. After the clasp 30 has been swung into open position as indicated by the dotted lines in Fig. 2 the hook 19 may be readily disconnected from the pin 28.

It will be observed from the above that 130

my invention provides a particularly simple and efficient device for securely clasping the ends of the bracelet together. The improved clasp-device is strong and sturdy in construction with its parts proof against derangement or getting out of order so as to render it durable over long periods of use.

When the clasp 30 is closed the cross-strip 31 fits snugly within the recess or cut-away portion 29 at the end of the box-link 23, alining with the top-portion 24 of the link and forming an unbroken surface therewith. There are therefore no unsightly joints or openings between the parts and no projections or irregularities liable to catch in the garments of the wearer.

While I have herein described and illustrated the improved device in a preferred form of construction by way of example, it is to be understood that various modifications may be made in the structure and arrangement of its parts without departing from the spirit or scope of the invention. Therefore without limiting myself in this respect

25 I claim:

1. In a clasp-device for bracelets or the like, the combination of a link having a cross-member at its end, a second link having a hook at its end adapted to hook around one side of the cross-member, and a pivoted clasp on one link provided with a latch adapted to slide across and engage with the cross-member on the opposite side from the hook.

35 2. In a clasp-device for bracelets or the like, the combination of a link-element having a cross-member at its end, a second link-element having a hook at its end adapted to hook partly around the cross-member on the first link-element, and a clasp pivoted to the sides of the first link-element and provided at its end with a latch adapted to be sprung into engagement with the cross-member on the opposite side from the hook.

45 3. In a clasp-device for bracelets or the like, the combination of a link-element having a cross-member at its end, a second link-element having a relatively wide hook at its end adapted to hook around the cross-member throughout its length and provided with an opening at its center, and a clasp pivoted to the first-link-element and provided with a relatively narrow latch at its end adapted to slide through the opening in

the hook on the second link-element and to frictionally engage with the cross-member on the opposite side from the hook.

4. In a clasp-device for bracelets or the like, the combination of a hollow box-link having a cross-member extending across its open end, a link-element having a relatively wide hook adapted to hook around said cross-member on the box-link and formed with an opening in its side, and a bifurcated clasp-member pivoted to the sides of the box-link and provided with a latch at its end adapted to slide through the opening in the hook on the link-element and to frictionally engage around the side of the cross-member in opposite relation to the hook.

5. In a clasp-device for watch-bracelets or the like, the combination of a box-link having a relatively flat top cut away at one end to provide a recess, a pin extending across the open end of the box-link, a bifurcated clasp-member having a cross-strip with arms extending therefrom in straddled relation with the sides of the box-link and pivoted thereto at their ends and a latch at the center of the cross-strip adapted to spring around the cross-pin on the box-link, and a second link having a relatively wide hook adapted to hook around the cross-pin on the box-link and provided with an opening in its side, the clasp being adapted to be closed into position with its cross-strip seated in the opening on the top of the box-link and its latch projecting through the opening in the hook on the second link with its end frictionally engaged with the cross-pin to hold the parts in connected relation.

6. In a bracelet or like article, the combination of tubular box-links, a slide slidable in one of the box-links with its end projecting therefrom and formed into a hook, a cross-pin extending across the opening in the next adjacent box-link to adapt it to be engaged by the hook on the slide, and a clasp-device comprising a bifurcated member pivoted on the last mentioned box-link and provided at its end with a latch adapted to slide past the hook on the slide-link to frictionally engage with the cross-pin to lock the parts in connected relation.

In testimony whereof I affix my signature.

ALMYR L. NEWMAN.
